UNITED STATES PATENT OFFICE

108,100

DESIGN FOR AN ADJUSTABLE METATARSAL INSOLE

Ross H. Johnson, Indianapolis, Ind.

Application February 8, 1937, Serial No. 67,509

Term of patent 14 years

To all whom it may concern:

Be it known that I, Ross H. Johnson, a citizen of the United States, residing at Indianapolis, county of Marion, and State of Indiana, have invented a new, original, and ornamental Design for an Adjustable Metatarsal Insole, of which the following is a specification, reference being had to the accompanying drawing forming part thereof.

Figure 1 is a top plan view of an adjustable metatarsal insole, showing my new design.

Figure 2 is a side elevational view of the same. The important features characterizing the present design consist in the arrangement of lines forming a design upon the surface of the insole.

I claim:

The ornamental design for an adjustable metatarsal insole, as shown and described.

ROSS H. JOHNSON.
